INSULATED PANEL

Ralph C. Parkes, Glenside, Pa.

Application October 27, 1955. Serial No. 543,208

4 Claims. (Cl. 189—34)

My invention relates to an insulated panel adapted to be used in building the walls, or the roofs, of various enclosures, such as heated or cooled chambers, or of the walls or roofs of ordinary buildings or wherever lightness, rigidity and minimum heat transfer are required.

One object of the invention is to produce an improved panel of the type set forth.

In order to minimize the cost of fabrication of individual panels and the cost of assembling or mounting them to form the desired enclosure, the panels should be made relatively large. But, if panels of this type are made relatively large, they will sag and warp even though they are made of a relatively heavy gauge metal.

It is therefore a further object of the invention to produce an improved panel which can be made relatively large and of relatively light gauge metal, but which will not sag or warp.

A still further object is to produce an improved panel which can be mass-produced and which is interchangeable, side to side and end to end whereby production and assembly costs are reduced.

The full nature of the invention will be understood from the following specifications and the accompanying drawings in which:

Fig. 1 is a reduced, highly diagrammatic top plan view of the two panels showing one embodiment of my invention only the outline of the panels and the outline of only some of the parts inside the panels being shown.

Fig. 2 is an end elevational view looking in the direction of line 2—2 on Fig. 1.

Fig. 3 is an enlarged, exploded, vertical, sectional view looking in the direction of line 3—3 on Fig. 1.

Fig. 4 is similar to Fig. 2, but showing a second embodiment of the invention.

Fig. 5 is similar to Fig. 3, but showing the panels of said second embodiment.

Fig. 6 is a fragmentary, enlarged, sectional view taken on line 6—6 on Fig. 2.

Fig. 7 is a vertical, sectional view, showing the panels of Fig. 5 in their assembled position.

Fig. 8 is an enlarged, perspective, exploded view showing the assembling and reinforcing members which are shown at the ends of Figs. 3, 5 and 7.

Fig. 9 is a diagrammatic, isometric view illustrating the manner in which the panels of my invention resist the stresses to which they are subjected in actual use.

In the embodiment of Figs. 1 and 2, each panel is formed of an outer sheet 16 and an inner sheet 18 with insulation 20 therebetween. The ends of the panels are closed by means of plates or sheets 22, which are flanged outwardly at 23 and are secured to the edges of sheets 16 and 18 by rivets or the like 24, as best shown in Figs. 2, 4 and 6. Sheets 16 and 18 may be made of aluminum or of stainless steel or other material.

In the embodiment of Fig. 1, one end 28 of outer sheet 16 of panel A is bent downwardly and laterally inwardly and cooperates with the corresponding upwardly and laterally outwardly bent end 30 of sheet 18, to form an

2

upper, reduced, overhanging pocket which is generally referred to be reference character 32. The adjacent end 34 of outer sheet 16 of adjacent panel B is bent downwardly and laterally outwardly and cooperates with corresponding upwardly and laterally inwardly bent end 36 of inner sheet 18 to form a pocket which is generally referred to by reference character 38 and which, when the panels are assembled will underlie overhanging pocket 32 as shown in outline in the center of Fig. 2. Since the junctions of all panels of this embodiment are the same as that described for the adjacent, overlapping junctions of panels A and B, it is believed unnecessary to further illustrate or describe this particular feature.

In order to make it possible to produce relatively large panels of relatively light gauge sheet metal which will not sag or warp, I have devised a novel construction which resembles a truss in its rigidity and its torque resisting characteristics. According to my invention, I place reinforcing and clamping blocks 40 of Fig. 8 in the corresponding sides of panels A and B and I place similar blocks 42 in the opposite corresponding sides of said panels. From Fig. 8 it will be seen that blocks 40 and 42 are L-shaped and from Figs. 2 and 3, it will be seen that blocks 40 and 42 assume the same relation in the assembled panels that they do in Fig. 8. In other words, the left hand overhanging portion of block 40 is enclosed in upper, overhanging pocket 32 of panel A and the right hand underlying portion of block 42 is enclosed in underlying pocket 38 of panel B. Blocks 40 and 42 are provided with through holes for receiving bolts 46 which secure the overlapping sides of panels A and B together. The inner ends of bolts 46 may pass through suitably spaced angles or girders 48 which constitute a supporting frame for a wall or roof built of these panels. It will be noted that the outer ends of bolts 46 threadedly engage nuts 50 which are placed in recesses which are spaced from outer sheets 16 so as to produce an unbroken, leak proof outer surface and to reduce thermal conductivity to the outer sheet. By this arrangement bolts 46 can be threaded into the nuts after being passed through angles 48 and blocks 42. It will also be seen that the edges 52 and 54 of outer and inner sheets 16 and 18 of panel A engage groove 56 in block 40 and that corresponding edges 58 and 60 of inner and outer sheets 16 and 18 of panel B engage groove 62 in block 42. Therefore, when the panels are assembled, as shown in Fig. 2, the marginal portions of inner and outer sheets 16 and 18 which terminate in edges 52, 54, 58 and 60 will be clamped between the flat surfaces 64 and 66 of blocks 40 and 42.

In order to minimize metal to metal contact and, hence, heat transmission, I place a heat insulating sheet 70 between blocks 40 and 42 and the contiguous portions of sheets 16 and 18 as shown in Fig. 3.

55 In order to tension outer and inner sheets 16 and 18 in the direction of their widths, I provide spaced turn buckles each of which consists of a hub adapted to abut a block 42 and a screw 74 threadedly engaging hub 72 and having a flange 76 for abutting a block 40. Blocks 40 and 42 are provided with through holes 78 through which a screw driver, or other tool, may be inserted to turn screw 74 in a direction to spread blocks 40 and 42 apart and thus tension sheets 16 and 18. The provision of holes 78 makes it possible to tension the sheets of each panel after it is completely formed and after one side of such panel has been securely clamped to the previous panel.

It will be seen from Fig. 1 that blocks 40 and 42 and turn buckles 72 are placed at intervals along the length of the panels, the distance between adjacent blocks being determined by the requirements of each case.

The construction thus far described is operative, but, for certain cases, it is desirable further to reinforce the

construction by means of rigid angles 80 which can extend the length of the panel or which may be long enough to be engaged by the spaced adjacent blocks 40 and 42. Angles 80 serve to transmit the tension applied to blocks 40 and 42 by turn buckle 72 to the areas of sheets 16 and 18 which are engaged by the angle irons. This can be readily seen from an inspection of Figs. 1 and 3.

The structure of Figs. 4 and 5 is the same as that of Fig. 1 except that in this embodiment, panel A' is provided with overhanging pockets 82 and 84 for receiving blocks 86 which correspond to blocks 40 and panel B' is provided with underlying pockets for receiving blocks 90 which correspond to blocks 42. Therefore, except for the fact that the overhanging or underlying marginal portions are on the same side of the panel, instead of being diagonally disposed, the structure of the embodiment of Figs. 4 and 5 is the same as that of the embodiment of Figs. 1 to 3.

In both embodiments, the engagement of edges 52 and 54 and 58 and 60 with grooves 56 and 52 and the clamping of the portions of sheets 16 and 18 adjacent these edges between surfaces 64 and 66 of blocks 40 and 42, effectively snub sheets 16 and 18 and resist any force tending to pull sheet 16, or sheet 18 of panel A or of panel B apart.

Also, a force exerted on the inner side of the panel in a direction parallel to the axis of bolt 46 will tend to separate the outside abutting edges of adjacent panels, and vice versa. But because blocks 40 and 42 are bolted together, the force exerted must be enough to deform, or break one or both of the blocks before separation or deformation of the panels can take place.

Sheets 16 and 18 are, in effect, the opposite sides of a beam and, therefore, a force which tends to put sheet 16 into compression, will tend to put sheet 18 into tension and vice versa. But, because, the ends of sheets 16 and 18 are securely clamped, neither sheet can move about the neutral axis of the beam and any force exerted on either side of the panel will be resisted by both of sheets 16 and 18.

As will be seen from diagrammatic Fig. 9, which may be taken as representing the construction of both embodiments, the panels described will partake of the characteristics of a truss. This attribute is derived from the fact that, when blocks 40 and 42 are spread apart, sheet 16, of either embodiment, will be subjected to a tensile stress in the direction of arrows Y-1 and Y-2; that, when sheet 16 is subjected to a vertical load, as viewed in Fig. 9, it will be subjected to compressive component in the direction of arrows Y-3 and Y-4 and that, when sheet 16 is subjected to a tensile load in the direction of arrows P-1 and P-2, it will be subjected to compressive load in the direction of arrows C and B. In other words, the blocks 40 and 42 and/or angles 80 serve as the sides and the tensioned portion of the sheet therebetween serves as the diagonal member of a truss which effectively resists the tendency of the panel to buckle in the direction of arrows Y-3 and Y-4, or in the direction of arrows C and B.

This application is a continuation in part of my pending application Ser. No. 407,308 filed February 1, 1954, entitled Insulated Panel.

What I claim is:

1. An insulated panel including a first relatively thin sheet, a second relatively thin sheet parallel to, spaced

from, and cooperating with, said first sheet to form a body portion of a predetermined thickness and first and second marginal portions of reduced thickness extending along the opposite ends of said body portion, the combined thicknesses of said first and second marginal portions being substantially equal to the thickness of said body portion, whereby, when a number of panels are arranged in contiguous co-planar positions with the first marginal portion of each panel overlapping the second marginal portion of an adjacent panel, a wall of uniform thickness is produced, a first block having a reduced portion snugly fitting in the first marginal portion of the panel and having an enlarged portion snugly fitting in the body portion of the panel, a second block having a reduced portion snugly fitting within the second marginal portion and having an enlarged portion snugly fitting within the body portion of the panel, and an expandable member located between the enlarged portion of said first and second blocks and pushing said blocks apart to tension said sheets, there being holes in the reduced portions of said first and second blocks for receiving bolts to clamp the first and second marginal portions of assembled panels together, and recesses in the sides of said blocks facing said sheets and accommodating nuts to be engaged by said bolts.

2. An assembly of panels each of which includes a first sheet, a second sheet parallel to, spaced from, and coacting with, said first sheet to form a body portion of a predetermined thickness and first and second marginal portions of a reduced thickness extending along the opposite ends of said body portion, with the first reduced marginal portion of each panel overlapping a second marginal reduced portion of an adjacent panel, a first block in the first marginal portion of each panel, a second block in the second marginal portion of each panel, the thicknesses of said blocks being substantially equal to the thicknesses of the respective marginal portions, an expansion member located between the blocks in the opposite reduced marginal portions of each panel and pushing said blocks apart to tension said first and second sheets, means clamping said first and second blocks together to secure the overlapping portions of said first and second sheets of each panel together and to the respective first and second sheets of adjacent panels, whereby pressure applied to a first sheet of one of said assembled panels will be transmitted to the second sheet of said panel and to the first and second sheets of said assembled panels, and means securing the portions of said first and second sheets, which form the marginal reduced portions along the outer ends of the outermost of said assembled panels to a rigid extraneous support.

3. The structure recited in claim 2 and an elongated rigid member placed between a block and the adjacent marginal wall to reinforce said wall and to distribute the concentrated pressure exerted by said blocks over the entire area of said wall.

4. The structure recited in claim 2 in which each of said blocks also includes a portion located in the body of the panel, the thickness of said block being substantially equal to the thickness of the body of the panel.
